CLAIM

The ornamental design for a magnetic key box as shown and described.

DESCRIPTION

FIG. 1 is a perspective view of a magnetic key box showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof; and,

FIG. 9 is an enlarged portion view taken from encircled portion labeled, "9," in FIG. 1.

The even dashed broken lines depict portions of the magnetic key box and form no part of the claimed design. The dot-dash line illustrates the boundary of the enlarged portion view of FIG. 9 shown in FIGS. 1 and 9 and forms no part of the claimed design.
